RECLINING LOUNGE CHAIR

Rollin Bert Trouslot, Jr., Redwood City, Calif.;
 Dorothy Trouslot administratrix of said Rollin
 Bert Trouslot, Jr., deceased

Application January 25, 1949, Serial No. 72,600

5 Claims. (Cl. 155—50)

1

The present invention relates to improvements in reclining lounge chairs, and the principal object of the invention is to provide a lounge chair of the character described which is particularly attractive in appearance, economic in structure, and comfortable in use.

More particularly it is proposed to provide a lounge chair comprising a seat frame and a back frame secured thereto with freedom of angular adjustment, the seat frame comprising a pair of frame members terminating at their rear ends in downwardly presented coils to form rear legs for the chair, and the back comprising a pair of corresponding frame members secured upon the ends of the coils so that both the seat and the back are supported by the coils and a seat occupant enjoys the springiness and elasticity of the coils while bearing on the back of the chair as well as on the seat thereof.

It is further proposed to provide a chair of the character described in which all portions in contact with a supporting surface are rounded and smooth to facilitate chair movement and to preserve the floor of the surface on which the chair rests.

It is further proposed to provide an all metal chair in which the seat and the back are formed by a series of parallel steel bands for the comfort of the seat occupant and in which a certain elasticity is imparted to the seat by a simple structural arrangement.

Further objects and advantages of my invention will appear as the specification proceeds, and the novel features of my invention will be fully defined in the claims attached hereto.

The preferred form of my invention is illustrated in the accompanying drawing, in which

Figure 1 shows a perspective view of my reclining lounge chair.

Figure 2, a fragmentary side view of the joints between the back and the seat with adjacent parts.

Figure 3, a rear view of the chair portion shown in Figure 2.

Figure 4, a sectional detail view illustrating the manner in which the bands are secured upon the frame, and

Figure 5, a rear view illustrating the fastening means.

While I have shown only the preferred form of my invention, I wish to have it understood that various changes and modifications may be made within the scope of the claims attached hereto without departing from the spirit of the invention.

2

Referring to the drawing in detail, my reclining lounge chair comprises in its principal features a seat frame 1 and a back frame 2.

The seat frame comprises two parallel side frame members 3 preferably made of tubular and metallic material and terminating at their rear ends in downwardly presented coils 4, the extreme ends 5 of the coils lying substantially within the plane of the frame and inwardly of the main sections of the side frame members. The said two end sections are interconnected by means of a cross-member 6.

At the front of the seat the side frame members 3 are bent downwards as at 7 to present front legs 8 which are interconnected, at their lower extremities by a cross-member 9 on curves 10 as shown.

In the form shown in the drawing my invention is intended for use as a lounge, and the seat is sufficiently long to accommodate the lower limbs of the occupant. There is a slight upward bend in the side members, approximately at knee position, as shown at 11, and at this point the two side members are interconnected by a transverse member 12. A further cross-member 13 is provided at the bends 11.

The extreme ends 5 of the coils 4 terminate in sockets 14 having brackets 15 secured therein as at 16. The brackets 15 are sector-shaped and are provided with a series of peripheral recesses 17. The back frame comprises two parallel side frame members 18 and transverse frame members 19, 20 and 21 respectively, and the side frame members are spaced to substantially correspond to the spacing between the two brackets 15.

The lower ends of the side frame members 18 terminate in sockets 22 having metal straps 23 projecting downwardly therefrom, the straps being adapted for lying against the inner faces of the brackets 15 and being pivotally secured thereto as at 24, at the axis of the sectors.

A rod 25 is slidably mounted in the two cross-members 19 and 20 and has a handle 26 projecting rearwardly from the upper end thereof. The lower end of the rod 25 carries a cross-rod 27 the ends of which are adapted for engagement in the notches 17 of the two sector-shaped brackets. A spring 28 urges the ends of the cross-rod into the notches for supporting the back in the angular position to which it has been adjusted.

The cross-rod 27 is slidable in slots 29 formed in the straps 23, and these slots are sufficiently long to allow the cross-rod to be retracted from engagement with the notches in the brackets. It

will be noted that underneath the lowermost notch 17 the bracket has a projecting tooth 30, and this tooth serves as a definite stop to prevent the back frame from swinging below horizontal position since the slots 29 do not allow the rod 27 to be lifted sufficiently high to avoid the stop 30 on the downward course of the back frame. Both the seat frame and the back frame are covered with a series of parallel metallic bands 31 which are preferably secured upon the respective frame members in the manner disclosed in Figures 4 and 5 in which the end of one band 31 is shown as being partly wrapped around the frame member identified as 21 and is secured thereto by means of a set of bolts or screws 32. The cross-member 12 gives a slight lift to the bands and provides for a certain springy action at the knee portion of the seat.

It will be noted that in this construction the downwardly presented coils 4 serve as legs for the rear end of the seat and at the same time as a supporting means for the back frame. The transverse frame members 6 and 19 are arranged comparatively close to the joints between the two frames so as to firmly hold the different parts in proper position. The rear frame may be readily adjusted by lifting the rod 25 and engaging the transverse rod 27 into the desired notch.

My lounge chair may, of course, be made of any suitable material, but in the preferred form the frame is preferably made of chrome steel and the bands should be made of rust-proof light-gauge steel.

It is apparent that if no lounging effect is desired the seat may be shortened to the length of an ordinary chair seat without involving invention.

I claim:

1. In a lounge chair, a seat frame comprising a pair of side frame members having downwardly presented coils at the rear ends thereof to form rear legs for the chair, the frame having a major portion projecting forwardly from the coils with independent means for supporting the front end thereof.

2. In a lounge chair, a seat frame comprising a pair of side frame members having downwardly presented coils at the rear ends thereof to form rear legs for the chair, the frame having a major portion projecting forwardly from the coils with independent means for supporting the front end thereof, and a back secured upon the coils substantially in the vertical plane of the axes thereof.

3. In a lounge chair, a seat frame comprising a

pair of side frame members having downwardly presented coils at the rear ends thereof to form rear legs for the chair, the coils terminating in horizontal sections substantially within the horizontal plane of the frame members, and a seat having its rear edge supported in said end sections and substantially in the vertical plane of the axes of the coils, with the major portion of the seat projecting forwardly from the coils.

4. In a lounge chair, a seat frame comprising a pair of side frame members having downwardly presented coils at the rear ends thereof to form rear legs for the chair, the coils terminating in horizontal sections substantially within the horizontal plane of the frame members, and a seat having its rear edge supported in said end sections and substantially in the vertical plane of the axes of the coils, with the major portion of the seat projecting forwardly from the coils, and with independent means for supporting the front end thereof.

5. In a lounge chair, a seat frame comprising a pair of side frame members having downwardly presented coils at the rear ends thereof to form rear legs for the chair, the coils terminating in horizontal sections substantially within the horizontal plane of the frame members, and a seat having its rear edge supported in said end sections and substantially in the vertical plane of the axes of the coils, with the major portion of the seat projecting forwardly from the coils, and with independent means for supporting the front end thereof, and the said horizontal coil sections having a back supported thereon immediately adjacent said vertical plane.
